UNITED STATES PATENT OFFICE.

LOUIS COURTOT, OF PARIS, FRANCE.

MEANS FOR FIXING FOUNDRY CORES IN MOLDS.

1,403,467.

Specification of Letters Patent. Patented Jan. 10, 1922.

Application filed May 28, 1920. Serial No. 385,001.

To all whom it may concern:

Be it known that I, LOUIS COURTOT, a citizen of the Republic of France, residing at Paris, Seine Department, No. 9 Rue Théodule Ribot, in the Republic of France, engineer, have invented certain new and useful Means for Fixing Foundry Cores in Molds, for which I have filed applications in France Feb. 7, 1919; Belgium Mar. 18, 1919, and in Italy Mar. 22, 1919, of which the following is a specification.

This invention relates to improvements in casting hollow bodies, and the same has for its object more particularly to provide means whereby the cores used in connection with the molds required for casting such hollow bodies or elements may be held positively in position within said molds during the pouring operation.

20 Further, said invention has for its object to provide means whereby the cores used in connection with molds for casting tubular bodies, pipes, radiator sections and other bodies having comparatively long or large internal cavities may be so held in position within the molds that the same will not become displaced by the pouring of the molten metal into the mold.

Further, said invention has for its object 30 to provide means for holding or fixing the core whereby to prevent all tendency thereof to float or sink during the pouring operation, and thus insure a uniform metal line in the finished casting.

35 Further, said invention has for its object to provide a holding or fixing means of the character specified, adapted to be inserted between the upper and the lower mold parts, and to engage the core, whereby all movements of the core with respect to the mold 40 will be effectively restrained.

Other objects will in part be obvious and in part be pointed out hereinafter.

To the attainment of the aforesaid objects 45 and ends my invention consists in the novel details of construction, and in the combination, connection and arrangement of parts hereinafter more fully described and then pointed out in the claims.

50 Various applications of this improved means of fixing cores are illustrated by way of example in the accompanying drawings in which:

Figure 1 is a cross section on the line 55 A—A of Fig. 2, of a mold ready for receiving the molten metal;

Fig. 2 is a section taken parallel to the axis of a core;

Figs. 3 to 8 are cross sections of six different constructional forms of the mold, and 60

Fig. 9 is a plan of the bottom part of the mold shown in Fig. 8, with a fixing member resting thereon.

Figs. 1 and 2 illustrate a pipe mold. In said figures *a* is the top part of the mold; 65 *b* is the bottom part of the mold; *c* is the core, and *d* is the member for fixing the core.

As shown in Fig. 1, the fixing means has, in the part where it is in contact with the core, the circular shape of the latter, and therefore its presence does not affect the cross sectional passage of the pipe. In some cases the core may be formed at the point where it is fixed, with a groove in which the fixing member engages, in order 75 not to diminish the thickness of the casting at that point.

As shown in Fig. 3, the fixing member, where it is in contact with the core, is made of V-shape so as to effect a better centering 80 of the core, and diminish the length of the fixing member. In such a case the core is formed at the point where the fixing member is applied, with a V-shaped fixing notch. This construction is employed where there 85 is no need to trouble about slightly diminishing the cross sectional passage of the pipe or tubes at the fixing point, as for example in pipes or radiators for heating.

Figs. 4, 5 and 6 show a cross section of a 90 mold for a radiator element comprising more than one tube.

In Fig. 4 the tubes constituting the radiator element, are plain, that is to say, without ribs or longitudinal beads. The drawing shows clearly the arrangement of the fixing member *d* which consists of a continuous strip or rod embracing all the tubes that constitute the element. This strip or rod bears upon the sand in the plane of the 100 joint of the mold on each side of the element and between the tubes.

In Fig. 5 the tubes have longitudinal ribs. In this example of the application of the invention, the improved fixing means follows 105 the profile of the longitudinal ribs *h* at the point where these ribs are situated in the plane substantially parallel with the joint of the mold, in order to obtain the largest bearing surface possible of the sand against 110 the mold.

In Fig. 6 the tubes are connected by a

web *m*. The fixing means in order to bear upon the sand of the mold between the tubes, is arranged at this point upon one of the faces of the web.

5 Fig. 7 is a cross section of a double tube mold. In this example of the application of this invention, since the bearing surface of the fixing means upon the sand of the mold between the two tubes, might be reduced to such an extent that the pressure exerted by the fixing means at this point would push back the sand with the result of shifting the core, there is arranged in the 10 mold a metal piece *l* which may or may not form part of the framing and against which the fixing means bear. This piece *l* may serve for one or more fixing means.

The fixing means are situated mainly above the core as shown in Figs. 1 to 9, in 20 such a manner as to oppose a vertical or oblique rising of the core at the moment of casting. Moreover, when the core is of fairly considerable length, it is necessary to support it underneath in order to prevent it 25 from giving away under its own weight, and in this case one or more fixing means are placed at *e*, as shown in Fig. 3.

Figs. 8 and 9 are views of a mold for a radiator element comprising a plurality of 30 tubes. The core *c* is held in this example by a fixing means composed of two wires *f* bent as shown in said figures for increasing the bearing surface of the fixing means upon the sand. These wires *f* are fastened 35 by welding or otherwise to metal plates *p*. This form of fixing means may be located similarly to those hereinbefore described, either above or below the core.

The improved fixing means shown in 40 Figs. 8 and 9 is illustrated by way of example as comprising two wires, but this form of fixing means may comprise only one or any desired number of wires spaced uniformly or non-uniformly apart.

45 The improved fixing means may be bent at their ends as shown in Fig. 4, either upwardly or downwardly, the bent portion entering the sand of the mold. In this manner a greater resistance to the lateral shifting of the core is obtained if required.

50 The different constructions illustrated in Figs. 1 to 9 are given solely by way of example; all other constructions of the improved fixing means may be employed without departing from the invention.

The fixing members are produced by bending, stamping, or molding, or generally by any process whatever, and are made of any metal which will not melt and which 60 will expand as little as possible in the mold at the time of casting.

65 These fixing members may consist of a thin strip of sheet metal, tinned or not, or of a section of a bar of rectangular or other shape, or of one or more wires. In the por-

tions bearing upon the sand of the mold, the section bar or the wire constituting the fixing member, may be flattened in order to provide a greater bearing surface upon the sand.

70

The improved fixing means allows of greatly simplifying the molding of parts with cores, such as for instance the elements of multiple-tube radiators. In the molding of this kind of articles a single fixing 75 strip, like the one shown in Figs. 4, 5 and 6, serves as a substitute for a plurality of ordinary core-supports.

Since the fixing means is placed along the line of the joint of the mold and does not 80 pass either through the sand of the mold nor through the core, the ramming of the sand can be performed more easily than when ordinary core-supports are employed embedded in the sand of the mold. Consequently, the improved fixing means allows of employing molding processes and mechanical ramming processes which cannot be employed with the ordinary core-supports.

Since the improved fixing means works in 90 tension, the quantity of metal necessary to form it is smaller than in the case of an ordinary support working in compression and bending. The metal of the improved fixing means welds better with the metal 95 of the cast article, and the fluid-tightness of the latter is better.

The main technical results of the use of the improved fixing means according to this invention may be summed up as follows:

100

A simplification of the molding due to the particular construction of this improved fixing means.

Since the improved fixing means is not embedded in the sand of the mold as is the 105 case with ordinary supports, molding processes and sand-ramming processes may be employed which are not possible with the ordinary supports.

The V-shaped construction of the improved fixing means assures a better centering of the cores.

The metal of the improved fixing means works in tension, and the core is held in place better.

115

The section of the improved fixing means may be smaller, and the metal of which the said means is composed welds better with the metal of the cast article.

In the case of multiple tubes only one continuous fixing strip is necessary where more than one ordinary support would be required.

120

In order that the improved fixing means shall resist exclusively or almost exclusively 125 by tension, the thrusts exerted by the cores under the influence of the molten metal, it is sufficient to give a rectangular shape to those portions of the fixing means which are disposed between the points where said 130

fixing means bears upon the sand of the mold, and the points where it bears upon the core.

The drawings show pipes whose area is circular in cross section; it must be understood however that the cross section of the pipes may be of any desired shape or form.

Having thus described my said invention what I claim and desire to secure by Letters 10 Patent is:—

1. A means for fixing foundry cores in casting molds, consisting of a metal strip of small section having straight portions adapted to be inserted between the parts of the 15 mold in the sand and bent portions between said straight portions, said bent portions being adapted to bear against the surface of the cores for the purpose of resisting the thrust of the latter by tension.

2. A means for fixing foundry cores in casting molds, consisting of a metal strip of small section having portions adapted to bear against the sand of the mold, portions adapted to bear against the cores, and 25 straight portions between the points where the aforesaid portions are respectively in contact with the sand of the mold and with the cores, for the purpose of ensuring that the fixing means will offer tensile resistance to the thrusts of the cores.

3. A means for fixing foundry cores in casting molds, which consists of a metal strip of small section so shaped as to be capable of being freely inserted between the 35 halves of the mold and of bearing against the cores, the portions of said strip that are comprised between the points intended to bear respectively against the mold and against the cores, being straight for the purpose of offering tensile resistance to the thrusts of the cores.

4. A means for fixing foundry cores in casting molds, consisting of a strip composed of parallel wires and metal plates 45 attached to said wires, said plates being designed to bear against the sand of the mold.

5. A means for fixing foundry cores in casting molds, consisting of a metal strip of small section adapted to be inserted between the halves of the mold and to bear against the cores, the ends of said strip being formed with hooks for entering the sand of one of the halves of the mold.

6. A means for fixing foundry cores in 55 casting molds, consisting of a thin relatively narrow metal strip, the bent portions of said strip being adapted to bear against the cores, whilst the intermediate portions are adapted to bear against one of the halves 60 of the mold in the intervals of space between the cores.

7. A means for fixing foundry cores in

casting-molds comprising a relatively narrow member having flat portions adapted to be inserted between the mold parts, and 65 an intermediate portion adapted to engage a core, and maintain the same duly positioned with respect to the molds.

8. A means for fixing foundry cores in casting-molds comprising a plurality of relatively narrow members having flat portions adapted to be inserted between the mold parts, and intermediate portions adapted to engage a core above and below its axis whereby to maintain the same suspended within the mold and spaced with respect to the walls thereof.

9. A means for fixing foundry cores in casting-molds comprising a relatively narrow member, having flat portions adapted 80 to be inserted between the mold parts, means on said flat portion adapted to be anchored in the mold, and an intermediate portion adapted to engage a core and maintain the same duly positioned with respect to the mold.

10. A means for fixing foundry cores in casting-molds, a relatively narrow member having a flat portion adapted to be inserted between the several mold parts and extend 90 across the same, and an intermediate portion conformed to and engaging the core and serving to maintain the same duly positioned with respect to the mold.

11. A means for fixing foundry cores in 95 casting-molds, a relatively narrow member having a flat portion adapted to be inserted between the several mold parts and extend across the same, and an angular intermediate portion engaging the core and serving 100 to maintain the same duly positioned with respect to the mold.

12. A means for fixing foundry cores in casting-molds comprising a support composed of a plurality of parallel longitudinal members, and bearing members secured to said longitudinal members, said bearing members being adapted to bear against the surfaces of said mold parts.

13. A means for fixing foundry cores in 110 casting molds consisting of a metal strip adapted to be inserted between the mold parts and to bear against the cores, and anchoring means at the ends of said strip adapted to be embedded in the sand of one 115 of said mold parts.

In testimony, that I claim the foregoing as my invention, I have signed my name in presence of two subscribing witnesses.

LOUIS COURTOT.
